UNITED STATES PATENT OFFICE.

CHARLES GOLDTHWAIT, OF WEYMOUTH, MASSACHUSETTS.

NECKTIE.

SPECIFICATION forming part of Letters Patent No. 449,775, dated April 7, 1891.

Application filed January 27, 1891. Serial No. 379,297. (No model.)

To all whom it may concern:

Be it known that I, CHARLES GOLDTHWAIT, of Weymouth, in the county of Norfolk, State of Massachusetts, have invented certain new and useful Improvements in Neckties, of which the following is a description sufficiently full, clear, and exact to enable any person skilled in the art or science to which said invention appertains to make and use the same, reference being had to the accompanying drawings, forming part of this specification, in which—

Figure 1 is an elevation showing my improved necktie in use; Fig. 2, a perspective view showing means for fastening the strap; Fig. 3, a sectional elevation showing the inner face of the tie; Fig. 4, a perspective view of the tube, and Fig. 5 an elevation of the wedge.

Like letters of reference indicate corresponding parts in the different figures of the drawings.

My invention relates especially to a combination strap and bow tie, which is particularly designed for use with "standing" collars; and it consists in certain novel features hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the bow, which is constructed as follows: A strap is folded to form loops b and passed in front of and through a flattened metallic tube B, the ends of the strap being sewed together within said loop. A center piece d covers the tube and passes across the center of the bow in the ordinary manner of ties of this description,

the ends of said piece being sewed together at h, as shown in Fig. 3. The neck-strap C is passed through the tube B behind the loops b, and the rear edges of the center piece d are sewed thereto at f, one end of said neck-strap being left free and extended beyond the edge, as at m. The opposite or longer end p of the neck-strap is in use passed around the collar in the ordinary manner and through the tube B, between the inner face of the loops b and itself. A wedge D comprises an approximately rectangular metallic plate having a facing t, of felt or similar rough flexible material. The broader edge of the wedge is provided with a button v. After the tie has been adjusted on the collar, as described, and the end p passed through the tube B the wedge D is inserted tightly in the tube between the body of the strap C and its end p, as shown in Fig. 2, crowding the free end of said strap tightly against the tube and preventing the tie from accidentally working loose on the collar. The ends m p of the strap may be disposed in any suitable manner under the garments, as shown in Fig. 1, and the device as thus constructed presents the general appearance of a bow tied in the neck-strap in the ordinary manner.

Having thus explained my invention, what I claim is—

In a necktie, a tubular metallic body, in combination with a strap looped to form a central bow and secured to said body, a neck-strap having one end secured to said body, and an adjusting-wedge, as D, fitted to enter said body and provided with a head or button, substantially as described.

CHARLES GOLDTHWAIT.
